J. S. DUNCAN.
PRINTING DEVICE.
APPLICATION FILED NOV. 28, 1910.

1,026,254.

Patented May 14, 1912.

UNITED STATES PATENT OFFICE.

JOSEPH S. DUNCAN, OF CHICAGO, ILLINOIS, ASSIGNOR TO ADDRESSOGRAPH COMPANY, OF CHICAGO, ILLINOIS, A CORPORATION OF ILLINOIS.

PRINTING DEVICE.

1,026,254.

Specification of Letters Patent.

Patented May 14, 1912.

Application filed November 28, 1910. Serial No. 594,480.

To all whom it may concern:

Be it known that I, JOSEPH S. DUNCAN, a citizen of the United States, residing at Chicago, in the county of Cook and State 5 of Illinois, have invented new and useful Improvements in Printing Devices, of which the following is a specification.

This invention relates to that class of printing devices which consists of a plate 10 having type characters stamped in relief thereon and adapted to be stored in accordance with a card index system, or stacked in a pile, and which are run through an addressing, or other printing machine, to 15 take an impression therefrom.

The object of this invention is to provide a printing device of this character with a detachable section preferably bearing printing characters and which can be replaced 20 as occasion may require for the purpose of maintaining the system up to date and with a minimum of expense.

A further object of the invention is to provide a printing device of this character 25 with a detachable section adapted to be readily engaged or disengaged therefrom and which can be read at the back as well as at the front of the device.

In the accompanying drawings I have 30 shown the invention embodied in several forms and referring thereto Figure 1 shows a flat printing plate with a detachable section at one end. Fig. 2 shows another form of printing plate with the intermediate portion thereof elevated above the edges and with a detachable section at one end. Fig. 3 shows the detachable section adjacent one side edge of the form of plate shown in Fig. 1. Fig. 4 shows the same arrangement 35 on a plate of the form shown in Fig. 2. Fig. 5 is a sectional view on the line 5—5 of Fig. 1. Fig. 6 is a similar view showing that portion which receives the detachable section depressed. Fig. 7 is a transverse 40 sectional view on the line 7—7 of Fig. 1. Fig. 8 is a transverse sectional view on the line 8—8 of Fig. 2. Figs. 9 and 10 are views similar to Figs. 7 and 8, respectively, showing that portion of the plate to receive 45 the detachable section depressed. Fig. 11 is a longitudinal sectional view on the line 11—11 of Fig. 3. Fig. 12 is a view similar to Fig. 11, showing that portion of the plate depressed to receive the detachable section. 50 Fig. 13 is a sectional view on the line 13—13

of Fig. 3. Fig. 14 is a sectional view on the line 14—14 of Fig. 4. Figs. 15 and 16 are views similar to Figs. 13 and 14, respectively, showing that portion of the plate to receive the detachable section depressed. 60

The printing device comprises a printing plate 1 having spacing flanges 2 on its side or end edges. The plate may be flat, as shown in Fig. 7, or it may be elevated between its side edges at 3, as shown in Fig. 8. These plates are stamped out of sheet metal and provided with printing characters constituting an address form, or any other suitable form, and are run through an addressing or other printing machine to take 70 an impression therefrom. These devices are used principally for printing addresses and are generally employed by those who send out many bills, circulars, or other printed matter regularly to the same customers, 75

such as gas, electric light, and telephone companies, publishers, bankers, brokers, insurance agents, manufacturers and others. In the case of gas companies it is often desirable to print other information along 80 with the address on the bill, such as the number of the ledger and page where the customer's account is kept and the number of his meter. In the case of telephone companies it is often desirable to print the number 85

of the telephone and the rate and amount of the bill. Publishers generally desire to print the date of the expiration of the subscription on the address of the wrapper inclosing the magazine or periodical. 90

It also happens, with more or less frequency, in the case of gas and electric light companies particularly, that a customer may move from one place to another which makes it necessary to change his 95 name on the printing device correspondingly. It is desirable to avoid the necessity of making an entirely new printing device when changes occur, such as those which have been mentioned, and others, to avoid 100

the trouble and expense incident thereto, by providing means which will permit the change of only a portion of the printing device. With this end in view I provide a detachable section 4 located at the end of 105 the printing plate (as shown in Figs. 1 and 2), or a detachable section 5 extending lengthwise of the plate, as shown in Figs. 3 and 4, and these detachable sections may be placed on the printing plates so that the 110

printing characters thereon will be in a higher plane than the printing characters on the plate, as shown in Figs. 5, 7 and 8, or the printing plate may be depressed at 5 6, as shown in Figs. 6, 9 and 10 to receive the detachable sections so that the printing characters thereon will lie in the same plane as the printing characters on the plate.

The detachable section may be secured to 10 the plate in any suitable manner but I have shown a simple way of doing this which will permit of the ready engagement of the section with the plate and disengagement therefrom and which embodies no loose 15 parts. The detachable section is provided with projections 7 at opposite edges, preferably at top and bottom edges, which have depressed portions 8 adapted to engage lips 9 struck up from the plate. The lips 9 project in one direction and the depressed 20 portions 8 project in the opposite direction so that by sliding the section lengthwise on the plate the depressed portions 8 may be engaged beneath the lips 9 until the shoulders 10 on the projections 7 engage the lips 9. This engagement of the projections on 25 the section and the lips on the plate will retain the section in proper position on the plate but to lock the section on the plate I prefer to provide a tongue 11 on the section 30 preferably on one edge thereof between the projections 7 and adapted to engage an opening 12 in the plate. After the section has been arranged in position on the plate 35 the tongue 11 can be pressed downward by any suitable instrument to engage the opening 12 and it will then lock the section on the plate. To detach the section the tongue can be lifted up from engagement with the 40 opening 12 by applying an instrument to the underside of the tongue and then the section can be slid lengthwise of the plate out of 45 engagement with the projections.

It is desirable to read, from the back of 50 the printing device, the printing form on the detachable section, and therefore I provide one or more openings in that part of the plate located beneath the detachable section. In Figs. 1 and 2 I have shown the 55 plate with openings 13, and in Figs. 3 and 4 I have shown the plate with a single opening 14, these openings being of sufficient size to enable the reading of the type form on the removable section from the back of the printing device. These openings do not materially weaken the plate.

For certain classes of work and in certain 60 addressing or printing machines it is immaterial whether or not the faces of the type characters on the detachable section lie in a plane above the faces of the type characters on the plate but for other work and in other machines it is desirable to have the faces of the type characters on the detachable section lie in the same plane as the faces of the 65

printing characters on the plate and this is readily accomplished by depressing the plate at 6 to receive the section, as shown in Fig. 6 and elsewhere.

The value and importance of my invention 70 in maintaining a system of printing addresses of this general character at a minimum cost will be readily understood. If the account is transferred to another ledger or page the detachable section shown in Fig. 75 1 would be changed, or if the subscription is renewed the detachable section shown in Fig. 2 would be changed. The same information may be provided on the detachable sections shown in Figs. 3 and 4 but I have 80 shown these sections provided with the form of a name to indicate another advantage of the invention. If the customer of a gas or electric light company moves from one location to another the detachable section bearing his name may be transferred to another plate bearing the new address number, and the old plate kept for the new occupant of the premises indicated by the address thereon. In this way the necessity of making new 85 plates or new sections is avoided because the sections bearing the names can be changed from one plate to another as the parties change their location. As the sections 5 are of considerable length a greater 90 95 number of interengaging projections, lips and tongues may be provided therefor than is necessary in the short sections 4.

These printing devices are readily made 100 and the detachable sections can be easily 100 and quickly applied to the plates or detached therefrom as occasion requires. The sections are engaged with the plates in a manner which will not interfere with the regular operation of the addressing or printing machine and it will be understood that the sections can be arranged on the plates in the 105 positions illustrated, or in any other desired position.

What I claim and desire to secure by Letter 110 Patent is:

1. A printing plate having a type form stamped in relief upon the front thereof and provided with an opening at one side of the type form, and a detachable printing plate 115 upon the front of the main plate extending across the opening and provided with printing characters stamped in relief thereon and exposed to view at the back of the main plate through the opening, substantially as 120 described.

2. A printing plate having a type form stamped in relief upon the front thereof and provided with an opening at one side of the form, lips struck up from the front of the plate at opposite sides of the opening, and a detachable printing plate upon the front of the main plate extending across the opening and provided with projections 125 engaging beneath the lips to hold the detach- 130

able plate in place, said detachable plate having printing characters stamped in relief thereon and exposed to view at the back of the main plate through the opening, substantially as described.

3. A printing plate having a type form stamped in relief thereon and provided with an opening at one side of the printing form, lips struck up from the plate at opposite 10 sides of the opening, a detachable printing plate extending across the opening and having projections engaging beneath the lips, said detachable plate having printing characters stamped in relief thereon and exposed 15 to view through the opening, and means carried by one of the plates and engaging the other plate to lock the detachable plate, substantially as described.

4. A printing plate having a type form 20 stamped in relief thereon and provided with an opening at one side of the form, lips struck up from the plate at opposite sides of the opening, a detachable printing plate extending across the opening and having 25 projections engaging beneath the lips and

provided with a locking tongue, the main plate having a seat to receive the tongue and lock the detachable plate in place, said detachable plate having printing characters stamped in relief thereon and exposed to 30 view through the opening, substantially as described.

5. A printing plate having a printing form stamped in relief thereon and provided with a depression located at one side 35 of the printing form, lips struck up from the plate at opposite sides of the depression, and a detachable printing plate fitted in the depression and provided with projections engaging beneath the tongues, said detachable plate having printing characters stamped in relief thereon, and the back of the depression having an opening to expose 40 the printing characters of the detachable plate, substantially as described.
